UNITED STATES PATENT OFFICE.

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY.

COMBINATION RIVETER.

Application filed November 12, 1920. Serial No. 423,538.

To all whom it may concern:

Be it known that I, FRANCIS A. JIMERSON, a citizen of the United States, a resident of Athens, county of Bradford, State of Pennsylvania, have invented certain new and useful Improvements in Combination Riveters, of which the following is a specification.

This invention relates to pneumatic tools, but more particularly to a combination riveter, and holder-on, which may be used either as a riveter or as a holder-on without operating the piston of the hammer proper so that no work in that case is done by the tool as a riveter.

15 The primary object of the invention is to improve upon such combination tools and enable both the riveting hammer and the bodily movement of the riveting hammer in the casing of the tool to be controlled by a 20 single throttle valve, different positions of which enable the machine to be used either as a riveter or as a holder-on.

In order to effect such advantageous control, the cylinder of the riveting hammer 25 may be provided with a plunger head in the casing of the machine, and ports in the single throttle valve cooperate with passages in the casing for controlling both the supply and exhaust of the machine, in such manner that the riveting hammer proper may 30 be actuated outwardly in the casing without operating the piston hammer in the hammer cylinder.

A small supply of motive fluid, as live air 35 may first be admitted behind the plunger head of the hammer cylinder without opening the main exhaust to the machine casing, and the hammer cylinder will be moved outward in the casing until the rivet set comes 40 in contact with the rivet, the outer casing being held from movement in any suitable manner as by means of a center at the back end of the casing. The hammer piston in the hammer cylinder will not operate how- 45 ever, until the throttle valve has been turned to admit full supply to the hammer cylinder while at the same time opening the main exhaust through the outer casing.

Further objects of the invention will hereinafter appear and to all of these ends the invention consists of the features of construction, arrangement of parts and combinations of elements substantially as hereinafter fully described and claimed in this

specification and shown in the accompanying drawings, in which—

Figure 1 is a longitudinal vertical sectional elevation of the machine showing the piston hammer of the riveter in one position, it being understood however that the main throttle valve is closed and the machine is not in operation.

Figure 2 is a horizontal sectional plan view of the outer casing and riveting hammer on the line 2—2 of Figure 3.

Figure 3 is a transverse sectional elevation partly broken away through the outer casing and riveting hammer on the line 3—3 of Figure 1 looking in the direction of the arrows,

Figure 4 is a transverse detail sectional elevation taken through one portion of the throttle valve on the line 4—4 of Figure 1 looking in the direction of the arrows,

Figure 5 is a detail transverse sectional elevation taken through the exhaust end of the throttle valve on the line 5—5 of Figure 1 looking in the direction of the arrows,

Figures 6 and 7 are detail diagrammatic longitudinal sectional views of the riveting hammer with the ports and passages in the hammer cylinder in the same plane to illustrate the valve action, and the piston hammer in two different positions.

Referring to the drawings, the machine is provided with a unitary casing A containing the riveting hammer proper, including the hammer cylinder B and piston hammer C and also containing a single main throttle valve C' which controls both the inlet D and the main exhaust E of the machine. The hammer cylinder B is provided with a plunger head F of any suitable construction and the hammer cylinder and head F are bodily movable longitudinally within the cylinder casing G preferably formed as an integral part of the outer casing A. The cylinder casing G may be closed at the back end by means of the plug H having the center J screwed therein for holding the casing stationary when the machine is used as a holder-on, and the front end of the cylinder casing G may be closed by suitable front head portions K and L preferably having the packing O between said head portions. The hammer cylinder B is adapted to receive the usual rivet set P. Suitable ports

and passages, to be described, are provided in the hammer cylinder B, for the distribution of fluid pressure behind and in front of the piston hammer C for actuating said hammer, said distribution being controlled by a suitable fluid actuated valve Q preferably a central type valve, as shown in this instance.

The casing A as shown is provided with 10 the handle extensions R and S preferably at each end in which the throttle valve C' is conveniently mounted preferably substantially parallel to the longitudinal axis of the casing. A supply passage T in the extension R leads from the inlet D to a point in the cylinder casing G rearward of the plunger head F of the hammer cylinder and a main exhaust passage U in the extension S leads from the forward end of the cylinder casing G to the valve C' and communicates through the valve with the main exhaust E.

The throttle valve C' comprises in this instance a hollow spindle V having a tapered 25 plug W at one end seated in a valve seat formed by the sleeve X carried by the extension R and provided with the ports Y co-operating with the smaller port a and the larger port b in the valve plug W. The 30 other end of the valve spindle V as shown is provided with the exhaust port c cooperating with the port d in the bearing sleeve e carried by the extension S. An outer sleeve or cylindrical handle f is suitably secured to the valve spindle V between the extensions R and S as by means of the set screw g so that the valve may be conveniently rotated about its longitudinal axis by hand and a compression spring h within 35 the end j of the handle f bears against the washer k and normally forces the valve plug W to its seat. A set screw g' in the valve C' acts as a stop to limit the rotation. Lock nuts o on the reduced exhaust end of the 40 valve spindle may be so adjusted as to prevent the valve from jamming in its taper seat which avoids the difficulty of jamming and hard operation which is apt to occur with ordinary taper valves. A suitable stop 45 in the form of a spring pin p seated in the extension S passes through the bearing sleeve e and is adapted to engage a notch or notches q in the valve spindle, in order to maintain the valve in any given position.

50 In the operation of the machine so far described, let it be assumed that in Figure 1, the throttle valve is in closed position. In starting the machine, rotation of the throttle valve and the tapered valve plug W in the 55 direction of the arrows r and s in Figures 4 and 5 will first bring the small port a into communication with the inlet D, thus admitting live air through the passage T behind the plunger head F of the riveting hammer, 60 without however opening the main exhaust

E through the port c in the throttle valve. Under this condition, the plunger F and the riveting hammer will be forced bodily outward in the cylinder casing G, thus permitting the machine to be operated as a holder-on. Further rotation of the throttle valve in the same direction will place the large port b in the tapered plug W in communication with the inlet D and at the same time the exhaust port c at the opposite end of the 70 throttle valve, will be placed in communication with the main exhaust passage U, permitting the exhaust pressure from the riveting hammer cylinder to escape from the cylinder casing G through the main exhaust 75 E in which case the riveting hammer begins to operate as a riveter, because until the main exhaust E was opened, the exhaust pressure from the riveting hammer could not escape and the hammer piston C could 80 not operate.

The operation of the fluid actuated valve Q in the riveting hammer can best be explained by reference to the diagrammatic views of Figures 6 and 7. The back end of 90 the riveting hammer cylinder B may be closed by means of the cap 2 having the ports 3 and 4 communicating with the space in the cylinder casing G behind the plunger head F supplied with fluid pressure from 95 the passage T.

In Figure 6 the piston hammer C is shown at the rear end of its stroke in position to be driven forwardly and the valve Q, in its forward position for starting. Motive fluid is admitted through the port 3 in the cap 2 and the port 5 in the cylinder B behind the piston hammer C, and as the piston is driven forwardly, and uncovers the timing port 6, 100 live air is admitted through said port, passage 7 and port 8 to the annular groove 9 leading to a point beneath the shoulder 10 of the valve Q, which forms a rearwardly acting pressure area.

When the piston C in its forward travel 105 next uncovers the exhaust port 11, pressure behind the piston is partially relieved since the pressure may exhaust out through port 12 to the space between the hammer cylinder B and the outer casing, which communicates with the main exhaust. By partially relieving the pressure behind the piston C in the rearward portion of the cylinder the valve Q is thrown out of the balance, because 110 pressure is thus relieved from the projected forwardly acting pressure areas of the valve, tending to hold the valve in its forward position. These forwardly acting pressure areas are constituted by the rearward rim of the 115 valve and the inner shoulders formed by the stepped portion of the valve body, which may together be termed projected areas. The live pressure constantly on the rearward shoulder 13 of the valve through ports 4, 120 14, and 15 then preponderates and operates 125

to throw the valve rearwardly to the position indicated in Figure 7. The valve is thrown rearwardly immediately after the piston C uncovers the exhaust port 11, so that practically no live air is allowed to escape through the exhaust. The velocity of the piston and expansion of the motive fluid carries the piston forward.

As the piston delivers its blow on the rivet set, live air passes through the port 15, around the annular groove 16 in the valve and through the port 17, passage 18 and port 19 at the forward end of the cylinder and in front of the piston. The live air port 15 is relatively small so that a full force of the blow is imparted to the rivet set or working tool. The piston is then ready for the rearward stroke, and provision is made for sufficient travel beyond the exhaust port 11 as indicated in Figure 7 to permit the air to be fully exhausted behind the piston.

With the valve in the position indicated in Figure 7, the piston, in traveling rearwardly on the return stroke first covers the exhaust port 11, and the air from behind the piston escapes through port 6, passage 7, port 8, groove 9, and under the shoulder 10 to the port 21 and through the passage 22 to the exhaust port 12, thus preventing pressure from accumulating behind the piston. When the timing port 6 is closed by the piston on its return stroke, pressure gradually builds up behind the piston due to compression of entrapped air, until the pressure acting on the forwardly operating projected areas of the valve Q is sufficient to overcome the pressure constantly on the rearwardly acting shoulder 13, which at this time is less than line pressure, due to throttling or wire drawing as the motive fluid flows through the small port 15. Live air pressure is also provided by this construction to cushion the piston on its rearward stroke.

The function of the small port 23 in the valve Q beneath the shoulder 13 is to admit live air to shift the valve and start the operation of the machine when the piston and valve are both at the extreme rearward position, as for instance when the machine is idle and pointing in an upward direction.

I claim:

1. A combination riveter and holder-on, comprising a casing having handle extensions at each end, a fluid operated riveting hammer bodily movable in said casing, a single throttle valve mounted in said handle extensions for controlling both the operation of the hammer and the bodily movement of the hammer in the said casing and a sleeve forming a handle for actuating the said valve, whereby the machine may be used either as a holder-on or as a riveter.

2. A combination riveter and holder-on, comprising a casing having handle extensions at each end, a fluid operated riveting

hammer bodily movable in said casing, ports and passages in the handle extensions leading to and from the casing and the hammer for the distribution of motive fluid to the machine, a single throttle valve mounted in said handle extensions for controlling both the operation of the hammer and the bodily movement of the hammer in the casing and a sleeve forming a handle for actuating said valve, whereby the hammer may be actuated outward in the casing to act as a holder-on without operating the hammer for riveting.

3. A combination riveter and holder-on, comprising a casing having handle extensions at each end, a fluid operated riveting hammer including a cylinder and a piston hammer reciprocating therein, said cylinder being movable in said casing and actuated by fluid pressure, a single throttle valve mounted in said handle extensions for controlling both the operation of the hammer and the movement of the hammer cylinder in the casing, a sleeve forming a handle for actuating said valve and ports in the valve cooperating with passages in the handle extensions leading to the casing whereby the hammer cylinder may be actuated outward in the casing to utilize the machine as a holder-on without operating the piston hammer in the cylinder.

4. A combination riveter and holder-on, comprising a casing having handle extensions at each end, a fluid operated riveting hammer including a cylinder and a piston hammer reciprocating therein, said cylinder having a head and being movable in said casing by fluid pressure, passages in the handle extensions for supplying and exhausting motive fluid to and from said casing and said cylinder, a single throttle valve mounted in said handle extensions for controlling both the said supply and exhaust passages and a sleeve forming a handle for actuating said valve, whereby the hammer cylinder may be actuated outward in the casing to utilize the machine as a holder-on without operating the piston hammer in the cylinder.

5. A combination riveter and holder-on, comprising a casing having handle extensions at each end, a fluid operated riveting hammer bodily movable in said casing and a single throttle valve mounted longitudinally in said handle extensions, substantially parallel to the axis of the casing, thereby forming a handle and also controlling both the operation of the hammer and the bodily movement of the hammer in the said casing, whereby the machine may be used either as a holder-on or as a riveter.

6. A combination riveter and holder-on, comprising a casing having handle extensions at each end, a fluid operated riveting hammer bodily movable in said casing, and

- a single throttle valve mounted longitudinally in said handle extensions substantially parallel to the axis of the casing, thereby forming a handle and also being rotatable about its own longitudinal axis for controlling both the operation of the hammer and the bodily movement of the hammer in the said casing, whereby the machine may be used either as a holder-on or a riveter.
- 10 7. A combination riveter and holder-on comprising a casing having handle extensions integral therewith at each end, a fluid operated riveting hammer bodily movable in said casing, a single throttle valve in said handle extensions substantially parallel to the axis of the casing, said valve comprising a hollow spindle, a sleeve forming a handle secured to the valve for rotating the valve and controlling both the operation of the hammer and the bodily movement of the hammer in the said casing, whereby the machine may be used either as a holder-on or a riveter.

In testimony whereof I have signed this specification.

FRANCIS A. JIMERSON.
